UNITED STATES PATENT OFFICE.

ALFRED A. CONWAY, OF LOYALIST, ALBERTA, CANADA.

PLUG TERMINAL.

Application filed June 8, 1925. Serial No. 35,754.

The present invention relates to terminals for use in connection with electricity, and has particular reference to terminals adapted for use in electromagnetic circuits.

5 An object of this invention is to provide a device of this character which may be used without the application of tools and still provide a firm and positive connection.

10 Another object of this invention is to provide a device to which a wire or the like may be attached without severing the wire or drawing the same through a hole.

15 A further object of this invention is to provide a device which may have its outer members thoroughly insulated so that there is no possibility of a short circuit occurring should a live wire fall upon the terminal.

20 A still further object of this invention is to provide a device through which a connection may be made or broken by a slight forward movement of the shell or head.

25 The above and various other objects and advantages of this invention will in part be described in, and in part be understood from the following detailed description of the present preferred embodiment, the same being illustrated in the accompanying drawing, wherein:

30 Fig. 1 is a transverse section taken longitudinally through a device constructed according to the present invention.

Fig. 2 is a detail side elevation of the same.

35 Fig. 3 is a longitudinal section taken through the body of the device.

Fig. 4 is a detail side elevation of the plunger or plug.

40 Fig. 5 is a transverse section taken on substantially the line 5—5 of Fig. 1 and looking in the direction of the arrows.

Fig. 6 is a transverse section taken on the line 6—6 of Fig. 1, and

Fig. 7 is a transverse section taken on the line 7—7 of Fig. 1.

45 Referring to the drawing, 10 designates a panel or board upon which this device may be mounted, and which has an opening 11 through which the bolt or stem 12 is adapted to pass. The lower end of the stem 12 is preferably threaded to receive a nut 13 or the like, and a washer 14 is preferably interposed between the inner side of the nut 13 and the panel 10 to provide a bearing surface for the nut.

55 The bolt 12 is provided with a head 15

upon the outer surface of which is mounted a yieldable ball member 16. The ball 16 is provided with a plurality of slots 17 which are adapted to make the ball 16 yieldable. A casing 18 is adapted to engage at its lower end the ball 16, and for this purpose is provided with a seat or groove 19 in which the ball 16 is firmly held in position. The casing 18 may be constructed of metal similar to that of the bolt 12 and ball 16.

The outer end of the casing 18 is preferably open and a yieldable plug or plunger 20 is adapted to be loosely mounted therein. A helical spring 21 is mounted within the 70 casing 18 and at one end engages the outer surface of the ball 16, and at the other end engages the inner end of the plunger 20.

An insulating shell or casing 22 is adapted to surround the casing 18, and at its lower end is provided with a shoulder or flange 23 which is adapted to engage the outer surface of the head 15 and the inner end of the casing 18. The plunger 20 is provided with a cap 24 which is preferably constructed of insulating material similar to the casing 22. The inner end of the cap 24 is loosely mounted upon the casing 22 so that it may freely slide thereupon.

In order to restrict the movement of the 85 plunger 20 and the cap 24, an opening 25 is provided at opposite sides of the cylinders 18 and 22, and a pin 26 is mounted in the plug 20 and at opposite ends extends through the plug so that it will loosely engage in the openings 25.

Intermediate the ends of the casings 18 and 22 there is provided an opening 27, and the plunger 20 has a slot or opening 28, which is adapted to register with the opening 27 when the plunger 20 is pressed inwardly, and a wire end 29 may be inserted therein.

In the operation of this device, the bolt 12 may be secured to a panel 10 by the nut 13, 100 and if desired the end of a wire may be inserted under the nut 13 in place of the washer 14. The cap 24 may then be pressed forwardly until the opening 28 in the plunger 20 registers with the opening 27 of the casings 18 and 22. The end of a wire or the like may then be inserted in the opening 28, and with the release of the pressure upon the cap 24 the helical spring 21 forces the plunger outwardly until the wire is 110

firmly held within the openings and against the plunger 20 and the casing 18.

It is, of course, understood that various changes and modifications may be made in the details of construction and design of the above specifically described embodiment of the invention without departing from the spirit thereof, such changes and modifications being restricted only by the scope of the following claims.

What is claimed is:

1. A terminal comprising a yieldable base, an inner and an outer casing secured to the base, said inner and outer casings having a slot in the side thereof, a plunger slidably mounted in said inner casing, said plunger having a transverse slot therein, and a cap secured to said plunger at the outer end thereof, said cap also being adapted to fit over the outer end of said outer casing.
2. A terminal comprising a base having a yieldable ball head, a casing adapted to be detachably mounted on said base, a plunger slidably mounted in said casing, stop means for determining the movement of said plunger, an insulating shell surrounding said casing, and an insulating cap mounted on

said plunger, said cap also being adapted to telescope said shell.

3. A terminal comprising a base having a yieldable ball head, a metallic casing having a groove in the inner lower end thereof, said head being adapted to seat in said groove, a plunger loosely mounted in said casing, a spring in said casing, said spring engaging the inner end of said plunger for urging the same outwardly, an insulating casing surrounding said metallic casing, said metallic and insulating casings having a transverse slot therein, said plunger having a transverse slot therein, an insulating cap for said plunger, and stop means for determining the movement of the plunger.

4. A terminal comprising a base having a split ball head, a casing adapted to be detachably mounted on said base, a plunger slidably mounted in said casing, stop means for determining the movement of said plunger, an insulating shell surrounding said casing, and an insulating cap mounted on said plunger, said cap when urged downwardly being adapted to telescope the upper end of said insulating shell.

ALFRED A. CONWAY.
